UNITED STATES PATENT OFFICE.

ALFRED GEORGE ELLIS, OF HALE, ENGLAND, ASSIGNOR TO WESTINGHOUSE ELECTRIC & MANUFACTURING COMPANY, A CORPORATION OF PENNSYLVANIA.

ELECTRICAL TRANSFORMER.

Application filed May 19, 1923, Serial No. 640,245, and in Great Britain June 20, 1922.

My invention relates to electrical transformers and has for its object to provide improved means for varying the ratio of transformation.

5 For this purpose it has heretofore been proposed for star-connected three-phase transformers to provide a rotatable switching device of the drum type within the casing of the transformer adapted to connect 10 different tappings from the transformer windings together to the neutral point.

In accordance with the present invention 15 different ratios of transformation are obtainable by means of a regulating switch located inside the transformer casing and comprising a plurality of fixed contacts connected with the several tappings of a transformer winding and one or more movable contacts adapted to be moved over the fixed 20 contacts by a combined rotational and translatory movement. Preferably a single movable contact is provided for each phase winding, the whole being mounted on a shaft rotatable from the exterior of the transformer 25 and having a screw-threaded portion mounted in a nut secured to the transformer casing. Any other suitable means may however be employed to impart the desired rotational and translatory movement to the movable contact or contacts. When tappings are 30 taken from the neutral ends of the phase windings each movable contact may be adapted to engage each fixed contact of its respective phase in turn whereas when the 35 tappings are taken from intermediate points only of the phase windings it may be adapted to bridge each pair of fixed contacts of its respective phase in turn.

In order that the invention may be more 40 clearly understood and readily carried into practice reference will now be made to the accompanying drawings wherein Figs. 1 and 2 represent by way of example partly dia-grammatic longitudinal sections through 45 transformers equipped with regulating switches in accordance with the invention.

In each form illustrated the transformer is of the three-phase star connected type and comprises phase windings 3 located within a 50 casing 4 in the usual manner, the regulating switch comprising three groups of fixed contacts 5 of any convenient type mounted on an insulating support 6 within the transformer casing and a rotatable shaft 7 carry-

ing three contact fingers 8 adapted to co- 55 operate with the groups of contacts 5. The shaft 7 has a screwed portion 9 at one end and is mounted at opposite ends in a bushing 10 and nut 11 secured to the casing 4, one end projecting from the latter and carrying a 60 hand-wheel 12 by which the shaft can be rotated.

In the form illustrated by Fig. 1 the free 65 ends 13 of the phase windings 3 are connected with separate line terminals not shown and tappings 14 from the neutral ends and intermediate points adjacent the neutral ends are connected with the groups of contacts 5. The contact fingers 8 are electrically connected by a metallic sleeve 15 which 70 is insulated from the shaft 7 by an insulating sleeve 16, and the pitch of the screw 9 is such that a single rotation of the hand-wheel 12 moves each finger 8 from engagement 75 with one fixed contact into engagement with the next adjacent contact of the same group. Consequently by simply rotating the hand-wheel 12 the ratio of transformation can be varied as desired within the 80 limits imposed by the number and location of the tappings.

In the form illustrated by Fig. 2 the free 85 ends of the phase windings 3 are connected with line terminals as before but the tappings 14 which are in this case indicated by the references *a* to *e* are taken from intermediate points only of the windings and are 90 respectively connected with the terminals of the groups 5 which are designated by like references, each tapping *d* being connected with two terminals as shown. The contact fingers 8 are insulated from each other being mounted directly upon an insulating sleeve 16 and are adapted to bridge pairs of adjacent contacts of their respective groups 5, the arrangement being such that the ratio of 95 transformation can be varied as desired in the same manner and within the same limits as before.

The several windings are so divided that 100 the steps from *a* to *b* and *b* to *c* are two and one-half percent of the whole winding, and the step from *c* to *d* and *d* to *e* are five percent of the whole winding.

The various stages in the connections are 105 as follows: With the brushes 8 making contact with the fingers *c*—*d*, the whole winding is in circuit. One complete rotation of the

handle 12 in the counter-clockwise direction turns the brushes completely around and brings them into position to make contact with the fingers $d-b$ in which position one 5 section, namely the section from c to b , is cut out, that is to say, the two and one-half percent reduction is made in the windings. If now the handle is turned a number of times to bring the brushes 8 into position to make 10 contact with the fingers $a-d$, the two portions of the winding $c-b$, $b-a$ will be cut out and a five percent reduction made. If the handle is now rotated in the opposite direction, i. e. clockwise, a sufficient number 15 of times to bring the brushes into the position $e-b$, the portions of the winding e to d and c to b are cut out, that is to say seven and one-half percent of the whole. Finally the handle is rotated to bring the brushes in 20 to position to make contact with the fingers $e-a$ in which the whole of the sections are cut out, that is to say ten percent of the winding is eliminated. The sequence of 25 positions is therefore $c-d$, $d-b$, $a-d$, $b-e$ and finally $e-a$.

In each construction a suitable indicating device 17 may be provided outside the transformer casing to indicate the positions to 30 which the hand-wheel or equivalent should be turned to effect the several connections.

The invention is not limited to three-phase transformers but is obviously applicable to single phase and poly-phase star-connected transformers, while the form of apparatus 35 illustrated by Fig. 2 of the drawings is also applicable to delta connected three-phase transformers.

Although I have described a specific embodiment of my invention, it will be obvious 40 to those skilled in the art that various modifications may be made in the details of construction and arrangement of parts without departing from the principles herein set forth. I desire, therefore, to be limited only 45 to the spirit and scope of my invention, as set forth in the appended claims.

I claim as my invention:

1. In a transformer structure, a casing, a plurality of windings therein, a plurality of stationary contact members connected to 50 said windings, a shaft mounted in said casing, means for longitudinally moving said shaft at uniform speed during rotation thereof, and contact members mounted on said shaft for engagement with said stationary 55 contact members.

2. In a transformer structure, a casing, a plurality of windings therein, a plurality of stationary contact members connected to said windings, a shaft mounted in said casing 60 adapted for rotational and longitudinal movement, and contact members mounted on said shaft for engagement with said stationary contact members, said shaft and its contact members constituting a neutral point in 65 the connection of said windings.

3. In a transformer structure, a casing, a threaded member mounted thereon, a plurality of windings in said casing, a plurality of stationary contact members connected to said 70 windings, a threaded shaft mounted in said threaded member and adapted for rotational and longitudinal movement in said casing, and contact members mounted on said shaft for engagement with said stationary contact 75 members.

4. In a transformer structure, a casing, a threaded member mounted thereon, a plurality of windings in said casing, a plurality of stationary contact members connected to 80 said windings, a threaded shaft mounted in said threaded member and adapted for rotational and longitudinal movement in said casing, and contact members mounted on said shaft for engagement with said stationary contact 85 members constituting a neutral point in the connection of said windings.

In testimony whereof, I have hereunto 90 subscribed my name this second day of May, 1923.

ALFRED GEORGE ELLIS.
